CLAIM

The ornamental design for a sphygmomanometer with electrocardiograph, as shown and described.

DESCRIPTION

FIG. 1 is a front, top, and right side perspective view of a sphygmomanometer with electrocardiograph showing our new design;

FIG. 2 is a rear, top, and left side perspective view thereof; FIG. 3 is a front, bottom, and right side perspective view thereof;

FIG. 4 is a rear, bottom, and right side perspective view thereof;

FIG. 5 is a front view thereof;

FIG. 6 is a rear view thereof;

FIG. 7 is a top view thereof;

FIG. 8 is a bottom view thereof;

FIG. 9 is a right side view thereof;

FIG. 10 is a left side view thereof; and,

FIG. 11 is a view taken from the direction of arrow line 11 of FIG. 9 thereof.

The broken lines shown in the figures illustrate portions of the sphygmomanometer with electrocardiograph that form no part of the claimed design.
